UNITED STATES PATENT OFFICE.

WILLIAM H. HORN, JR., OF PHILADELPHIA, PENNSYLVANIA, ASSIGNOR TO WM. H. HORN & BROTHER, OF PHILADELPHIA, PENNSYLVANIA, A CORPORATION OF PENNSYLVANIA.

INSTEP-SUPPORT.

1,140,159.

Specification of Letters Patent. Patented May 18, 1915.

Application filed August 21, 1913. Serial No. 786,029.

To all whom it may concern:

Be it known that I, WILLIAM H. HORN, Jr., a citizen of the United States, residing in Philadelphia, Pennsylvania, have invented certain Improvements in Instep-Supports, of which the following is a specification.

My invention relates to structures particularly designed for application to the interior of a shoe for the purpose of locally supporting various portions of the foot, one object of the present invention being to provide a novel attachment for use in connection with an arch prop or instep support and particularly designed to support the metatarsal arch of the foot.

Another object of the invention is to provide a novel device of the general character above noted which may be conveniently attached to the leather cover or sole piece of an instep support of any desired form, for the purpose of raising or supporting the metatarsal arch of the foot at any desired portion thereof, the construction of the device being simple, inexpensive and of such a nature as to permit of its being quickly and conveniently applied to the sole piece of an instep support at any desired point thereof.

These objects and other advantageous ends I secure as hereinafter set forth, reference being had to the accompanying drawings, in which,

Figure 1 is an inverted plan of an instep support showing my invention as applied thereto, and Fig. 2 is a longitudinal section taken through an instep support of the construction shown in Fig. 1, further illustrating my invention.

In the above drawings, 1 represents a relatively stiff bridge piece of sheet metal connected by rivets 2 to a sole piece 3 of leather whose shape is such as to cause it to snugly fit within the shoe. Said bridge piece 1 is curved longitudinally as well as transversely in the well known manner to cause it to conform to the contour of the under surface of a normal instep, and the sole piece 3 is likewise formed to approximately the same contour, although it preferably projects beyond the edges of the bridge piece.

As will be understood by those skilled in the art, the toe end 4 of the sole piece lies for the most part directly under the metatarsal arch of the foot when the instep support is mounted in a shoe, and for the pur-

pose of giving local support to said arch, I attach to the under side of this end of the sole piece a substantially conical button or washer 5, which is usually so placed that it projects to a greater or less extent between the end of the metal piece 1 and the leather sole piece 3.

The button or washer itself consists of a suitably skived leather piece (although it may be made of other material if desired) held to the sole piece by means of an eyelet or rivet 6 passing centrally through it and serving to fixedly hold it to said sole piece. Obviously, this metatarsal arch support may be fixed to the toe end 4 of the sole piece 3 at any desired point depending on what particular part of the arch requires support, and it is preferably attached to the sole piece while the latter is in a moistened and therefore relatively pliable condition, after which the whole is so formed that the washer or button 5 is caused to bulge upwardly the part of the leather sole piece to which it is fixed. When the latter has dried and is ready for use, the flat base of the piece 5 is substantially flush with the under surface of the adjacent portions of the toe end of said sole piece. As a result of this formation, the generally convex upper surface of the sole piece 3 has a slightly rounded bulge or projection immediately over the metatarsal arch supporting piece 5, as shown in Fig. 2, so that when the arch support is placed within the shoe, there is provided a localized extra support for that particular part of the metatarsal arch immediately over the upwardly bulged part 7 of the sole piece 3.

Under conditions of use the previously formed, leather arch-supporting pieces 5 are supplied to shoe makers and dealers, together with the necessary eyeleting tools so that said pieces may be applied to ordinary instep support at whatever points they may be required. It is of course, obvious that the piece 5 as well as the sole piece 3 may be constructed of any suitable material, although I preferably make them of leather.

I claim:

1. The combination of an arch support including a sole piece; and a metatarsal arch-supporting piece in the form of a disk tapering from its center to its edges; with means passing through its center whereby it is attached to said sole piece.

110

2. The combination of an arch support including a leather sole piece; with a substantially circular piece on the under side of the front portion of said sole piece in position to locally support the metatarsal arch; and an eyelet connecting the sole piece and said circular piece.

In testimony whereof, I have signed my name to this specification, in the presence of two subscribing witnesses.

WILLIAM H. HORN, JR.
